Specification for Design.

Patented Nov. 22, 1921.

Application filed July 1, 1921. Serial No. 481,952. Term of patent 14 years.

To all whom it may concern:

Be it known that I, ERNST WALTER PLATE, a citizen of the United States, residing at Philadelphia, in the county of Philadelphia and State of Pennsylvania, have invented a new, original, and ornamental Design for a Bridge for String Musical Instruments, of which the following is a specification, reference being had to the accompanying drawing, forming part thereof.

Figure 1, is a face view of a bridge for

string musical instruments showing my new design.

Fig. 2, is a side elevation or edge view thereof showing the slotted lower end to simulate feet; and

Fig. 3 is a bottom view thereof.

I claim:

The ornamental design for a bridge for string musical instruments, as shown.

ERNST WALTER PLATE.
